W. H. WINEMAN

FORGE

Filed Oct. 29, 1921

UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

FORGE.

Application filed October 29, 1921. Serial No. 511,417.

To all whom it may concern:

Be it known that I, WADE H. WINEMAN, a citizen of the United States, residing at Chicago, in the county of Cook and State of Illinois, have invented certain new and useful Improvements in Forges, of which the following is a full, clear, and exact specification:

My invention relates to forges.

10 It has for its object to provide an improved forge, and more especially to provide an improved forge or furnace adapted to heat drill steels or similar small articles and wherein the fuel consumption is materially reduced at the same time that the efficiency of the furnace is maintained at the desired high standard. These and other advantages of my improved construction will, however, hereinafter appear.

15 In the accompanying drawings I have shown for purposes of illustration three embodiments which my invention may assume in practice.

In these drawings,

20 Fig. 1 is a longitudinal sectional view of one form of my improvement.

Fig. 2 is a transverse sectional view on line 2-2 of Fig. 1.

25 Fig. 3 is a view similar to Fig. 2 showing the parts adapted for heating different articles.

Fig. 4 is a similar view of a further modified construction.

In the illustrative form of my invention shown in Figs. 1 and 2, it will be noted that I have shown a furnace of the gas or oil type adapted to be supplied with a suitable mixture of oil or gas through a vaporizer or burner 1 connected to suitable sources of supply 2 and 3 and controlled by a suitable valve 4, the vaporizer or burner delivering into a furnace body 5 carried on suitable supports 6.

40 In my improved construction I provide a short, longitudinally disposed combustion chamber 7 aligned with and receiving the products of combustion from the vaporizer or burner 1 and directing the same upward through a narrow passage 8, herein of the same length as the chamber 7 and formed by overhanging fire brick 9. Herein, the work is also supported on the bricks 9 with the portions thereof to be heated overhanging the edges of the brick in the path of the products of combustion but preferably with

its extremities out of contact with the back wall of the passage. In my improved construction, the products of combustion, after acting upon the ends of the work supported on the fire brick 9, also pass up into and reversely longitudinally in an enlarged chamber 10 which is disposed parallel to the chamber 7 and extends backward over the burner 1 and toward the opposite end of the furnace body 5 to a suitable, herein upstanding, flue 65 or chimney 11. It will here also be noted that the heated gases in their passage through this chamber act on other articles to be heated supported on fire brick 12, corresponding to the bricks 9 but disposed at a higher level 70 than the fire brick 9, the articles to be heated similarly overhanging the edge of the brick so that the heated gases have access to the full surfaces desired to be heated.

75 As a result of my improved construction, utilizing a small combustion chamber, it will be noted that the fuel consumption is reduced, the reduction in fuel consumption varying substantially in proportion to the size of the chamber. It will further be evident that the heat generated in this chamber will act directly upon the work resting on the fire brick 9, the portions of which to be heated are disposed directly in the path of the products of combustion as they pass 80 up out of the chamber 7. At the same time, it will be noted that not only is the heat utilized to bring the group of objects to be heated resting on the brick 9, to the desired 85 maximum temperature but that the same 90 products of combustion acting upon these articles is utilized thereafter to bring the articles resting on the fire brick 12 to a very high temperature but slightly less than the temperature of the first mentioned group 95 of articles. In the use of my improved furnace, and especially when the chamber 10 is relatively longer than shown, the articles to be heated may be placed on the brick 12 at the right hand end and moved progressively 100 over those brick and over the brick 9 as the articles at the left hand end of the latter bricks are removed from the furnace. Attention is also directed to the fact that in 105 my improved construction due to the transverse path of movement of the gases, especially from the chamber 7, difficulty with unnecessary and objectionable heating of the portions of the work to be handled is minimized.

In the form of my invention shown in Fig. 3, it will be noted that the same disposition of the articles to be heated in different chambers and planes is utilized, but that the 5 articles to be heated lie not only on fire brick 9, 12 but on cooperating fire brick 9', 12', spaced apart from the bricks 9 and 12 and cooperating with the latter bricks to form work supports. By this construction it will 10 be noted that it is possible to heat an intermediate portion of the articles to be heated without at the same time increasing the temperature of the extremity of the article to the same degree, a feature of marked advantage in heating such articles, for example, as drill shanks wherein it is desired to heat the portion to be worked or forged without bringing the extremity of the steel to the same temperature. Obviously, this result 15 20 may be obtained in different ways, but I herein obtain the same through shifting the bricks 13, 14 laterally in suitable guides 13', 14' formed on the casing 5, to provide the desired space on top of the bricks 9', 12'. 25 In the form of my invention shown in Fig. 4 illustrating a modified form of my invention which may be used, if desired, it will be noted that advantage is taken of the reflected heat passing up out of a longitudinally disposed chamber 15, laterally adjustable projecting bricks 16 being provided over an upper chamber outlet 17 and having the function of reflecting the heat against the extremities of the work which 30 35 rests on the bricks 18 and projects over into the flue and under the bricks 16, the bricks 19 which support the bricks 16 also cooperating in obtaining this result.

While I have in this application specifically described three forms which my invention may assume in practice, it will be understood that these forms of the same are shown for purposes of illustration and that the invention may be modified and embodied 40 45 in various other forms without departing from its spirit or the scope of the appended claims.

What I claim as new and desire to secure by Letters Patent is:

- 50 1. In a forge, means forming a small combustion chamber having a restricted outlet and a larger communicating chamber, and means for supporting certain of the articles to be heated over said outlet and other articles in said communicating chamber.
- 55 2. In a forge, means forming a plurality of communicating heating zones having provision for permitting free lateral transfer of work from one zone to another.
- 60 3. In a forge, means forming a small heating zone and a communicating larger pre-heating zone having provision for permitting the free lateral transfer of work from one zone to another.
- 65 4. In a forge, means forming a combustion

chamber having an outlet and a laterally located communicating pre-heating portion and having provision for supporting the articles to be heated both in said pre-heating portion and transversely over said outlet 70 transversely of the path of the heated gases.

5. In a forge, means forming communicating heating and preheating zones each having an opening in its front permitting the free lateral transfer of a plurality of 75 articles to be heated, and means for directing the flow of gases transversely across said openings.

6. In a forge, means forming communicating heating zones adapted to receive articles to be heated from the same direction and to permit free lateral transfer of articles between zones and having provision for passing the heated gases in a direction transverse to said direction. 80 85

7. In a forge, means forming a combustion chamber having a restricted outlet and a communicating laterally located portion, and means for supporting certain of the articles to be heated over said outlet and other 90 articles in said communicating portion. 95

8. In a forge, means forming a combustion chamber having a laterally elongated outlet and a communicating laterally located portion, and means for supporting certain of the articles to be heated over said outlet and other articles in said communicating portion. 100

9. In a forge, means forming a combustion chamber having an outlet and a communicating chamber leading in the opposite direction from the direction in which products of combustion are supplied to said combustion chamber, and means for supporting articles to be heated over said outlet and in said communicating chamber. 105

10. In a forge, means forming a combustion chamber having an upwardly disposed outlet and a laterally located portion communicating with said outlet, and means for supporting articles to be heated in different planes over said outlet and in said portion and in the path of the products of combustion. 110

11. In a forge, means forming a combustion chamber having an elongated outlet and a communicating pre-heating chamber, and means for supporting certain of the articles to be heated over said outlet and transversely thereof and other articles in said pre-heating chamber with only an intermediate portion of said articles in the path of the products of combustion. 115 120

12. In a forge, means forming a combustion chamber having an outlet and a communicating pre-heating chamber, and means for supporting certain articles to be heated transversely over said outlet with an intermediate portion thereof in the path of the products of combustion and other articles 125 to be heated in said communicating chamber. 130

13. In a forge, means forming a combustion chamber having an elongated outlet and a communicating pre-heating chamber, means for supporting an article to be heated over said outlet and transversely thereof, and horizontally disposed laterally adjustable means reflecting heat on said article including a reflecting element disposed above the extremity thereof.
- 10 14. In a forge, means forming a combustion chamber having an outlet and a communicating chamber, means for supporting certain of the articles to be heated over said outlet and other articles in said communicating chamber, and means for reflecting heat upon certain articles including a reflecting element disposed above the extremities thereof.
- 15 15. In a forge, means forming a combustion chamber having a narrow longitudinally disposed upper outlet and a communicating chamber disposed in the same direction as said outlet and overhanging one end of said combustion chamber, a burner opening into said combustion chamber and disposed beneath said communicating chamber, and means for supporting articles to be heated over said outlet and in said communicating chamber.
- 20 16. In a forge, means forming communicating heating and pre-heating zones disposed in different vertically disposed horizontal planes, and means permitting free lateral transfer of work from said pre-heating zone to said heating zone.
- 25 17. In a forge, a combustion chamber and a laterally projecting pre-heating portion, a burner discharging laterally of said combustion chamber and means permitting the free transfer of work from said preheating portion to said first mentioned chamber.
- 30 18. In a forge, a combustion chamber having a burner discharging therein, and a pre-heating chamber projecting in a direction opposite from the burner discharge, and means permitting free lateral transfer of work from said pre-heating chamber to said chamber in the direction of the burner discharge.
- 35 19. In a forge, a combustion chamber having work supporting portions disposed in different vertically disposed horizontal planes, and means permitting free lateral transfer of work from one supporting portion to another.
- 40 20. In a forge, a horizontally disposed combustion chamber provided with a reduced pre-heating chamber and a flue communicating therewith, a burner discharging into said first mentioned chamber, and means permitting the free transfer of work from a point adjacent said flue in the direction of the burner discharge.
- 45 21. In a forge, means forming a combustion chamber having an elongated outlet, means for supporting an article to be heated over said outlet and transversely thereof, and means for reflecting heat longitudinally and downwardly on said article including an adjustable reflecting element disposed above the portion to be heated.
- 50 22. In a forge, means forming a plurality of communicating heating chambers and including a flue, said chambers having a provision for permitting free lateral transfer of work from one chamber to another in a direction away from said flue.
- 55 23. In a forge, means forming communicating heating and pre-heating zones disposed in different vertically disposed horizontal planes and adapted to receive the articles to be heated in the same direction, and means permitting transfer of work from said pre-heating zone to said heating zone.
- 60 24. In a forge, means forming a combustion chamber having an elongated outlet and a communicating pre-heating chamber, means for supporting an article to be heated over said outlet and transversely thereof, and means reflecting heat on said article including a reflecting element disposed above the extremity thereof.
- 65 25. In a forge, means forming a combustion chamber having a laterally elongated outlet and a communicating laterally located pre-heating portion, and means for supporting articles to be heated over said outlet and in said communicating pre-heating portion.

In testimony whereof I affix my signature.

WADE H. WINEMAN.
